UNITED STATES PATENT OFFICE.

FRED ZINIS, OF WASHINGTON, DISTRICT OF COLUMBIA.

NECKTIE HOLDER.

Application filed April 9, 1925. Serial No. 21,914.

This invention relates to necktie holders and has special reference to a necktie holder particularly adapted for use in connection with scarfs of the type generally known as "four-in-hand", the same being the long scarf usually worn by men for dress in the morning and afternoon.

One important object of the invention is to improve the general construction of devices of this character.

A second important object of the invention is to provide an improved necktie holder which is especially adapted for use with turn over collars, the holder being so constructed that it is adjustable to cause a necktie to fit properly on any height of collar.

A third important object of the invention is to provide, in a necktie holder of this character, elastic means having an adjustable tension so that the necktie can be caused to fit properly with reference to the collar.

A fourth important object of this invention is to provide an improved bendable wire frame for a made up necktie.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

35 Figure 1 is a rear view of a necktie showing the holder in position thereon.

Figure 2 is an enlarged detail view of the holder removed from the tie.

Figure 3 is a longitudinal section on the line 3—3 of Figure 2.

Figure 4 is a section on the line 4—4 of Figure 2.

Figure 5 is a section on the line 5—5 of Figure 2.

45 Figure 6 is a detail view of the wire frame used with the tie.

In the embodiment of the invention here illustrated the tie is shown at T. This tie is made up over a wire frame 10 properly shaped, as shown in Figure 6 and this frame may be bent to suit the size of the collar so that the tie may fit any size neck without either bulging the collar outwardly or pressing it in against the neck. At the top portion of the tie between the legs of the frame

10 is secured a plate having a main portion 11 and offset ends 12 provided with eyes 13 by which it is sewed to the tie. This plate is provided with an elongated slot 14 of proper size to permit the passage of the 60 head of a collar button 15, this being the ordinary neck button of the shirt and forming in itself no part of the invention, although it cooperates therewith. Slidably mounted on the plate 11 is a slide 16 the 65 side edges of which are bent around the plate so as to hold the slide thereon. This slide is provided with a slot 17 the lower end of which is wide enough to permit the passage of the head of the button 15, while the 70 upper end is so reduced in size that the shank of the button fits closely therein and thus the head cannot pull out. At the lower end of this slide is a cross bar 18 around which is laid or otherwise fastened, as may be found 75 desirable, a strip of elastic webbing 19 which passes down the plate 11 and hangs below the lower end thereof. On the lower end of the plate 11 is a pair of ears 20 wherein is pivoted a clasp 21 of the ordinary type. The 80 elastic web 17 passes beneath this clasp and by means of the clasp the length of the web between the slide and clasp may be regulated. Also, the position of the slide is thereby regulated. Now it is obvious that 85 with a high collar the necktie must project further above the collar button than with a low collar. Consequently, the slide 16 is adjusted closer to the lower end of the plate 11 for a high collar than for a low collar. 90 Moreover, the adjustment is so made that when the collar button 15 is engaged in the slot 17 the web 19 will always be somewhat stretched so as to hold the necktie properly up in the collar. In use, after the adjustment is made, the necktie is simply placed in front of the shirt and the slot 17 hooked on to the collar button 15. The arms of the frame 10 are, of course, bent to suit the neck. When thus arranged and the web 19 properly 95 adjusted the tie will at all times remain in proper position on the wearer.

There has thus been provided a simple and efficient device of the kind described and for the purpose specified.

105 It is obvious that minor changes may be made in the form and construction of the invention without departing from the material spirit thereof. It is not, therefore, desired to confine the invention to the exact 110

form herein shown and described, but it is desired to include all such as properly come within the scope claimed.

Having thus described the invention, what is claimed as new, is:

5. 1. In a device of the kind described, a plate adapted to be secured to the rear upper portion of a necktie, a slide mounted to slide on said plate and provided with a collar button 10 ton engaging slot, elastic means urging said slide toward the lower end of said plate, and means to regulate the length of said elastic means.

2. In a device of the kind described, a plate adapted to be secured to the rear upper portion of a necktie, a slide mounted on said plate and provided with a collar button engaging slot, an elastic web secured to said slide and depending therefrom, and a clasp mounted on the plate at the lower end thereof and beneath which said web passes, said clasp being arranged to grip the web and hold the same adjusted.
